UNITED STATES PATENT OFFICE.

GEORGE T. WARWICK, OF SPRINGFIELD, MASSACHUSETTS.

SAFETY-BICYCLE.

SPECIFICATION forming part of Letters Patent No. 399,455, dated March 12, 1889.

Application filed September 3, 1888. Serial No. 284,439. (No model.)

To all whom it may concern:

Be it known that I, GEORGE T. WARWICK, a citizen of Great Britain, residing at Springfield, in the county of Hampden and State of Massachusetts, have invented new and useful Improvements in Safety-Bicycles, of which the following is a specification.

This invention particularly relates to the class of road-vehicles known as "safety-bicycles;" and it consists, first, in the construction of the main supporting-frame, and, secondly, in the construction of steering mechanism, whereby on the turning of the handle-lever a less extent of rotary motion is imparted to the front fork and front or steering wheel carried thereby; and the invention consists in the construction and combination of parts, substantially as will hereinafter fully appear, and in accordance with the claims hereinafter recited.

In the accompanying drawings the form of machine known as a "safety-bicycle" is illustrated, and Figure 1 is a side elevation with the head portion in central vertical section for better illustration. Fig. 2 is a plan view of the machine; and Fig. 3 is a sectional view of the frame on the line 3 3, parts of said frame beyond such section being shown in rear elevation. In Sheet 2, Fig. 4 is a plan view, enlarged, of the motion-reducing mechanism between the steering-spindle and front-fork spindle, partially shown in the preceding figures. Figs. 5 and 6 are representations of two modified constructions of the motion-reducing mechanism, and to be considered as within the terms of the claim to such mechanism.

Similar characters indicate corresponding parts in all the views.

40 A and B represent the forward and rear wheels of the safety-bicycle, of or substantially of the same size and form.

C represents the frame comprising the backbone a for the front wheel, the fork b to horizontally embrace the rear wheel and support same in bearings carried at the outer ends of the legs thereof, and intermediately of said backbone and fork a horizontal portion, d, for suspending certain of the essential parts and mechanisms, as the saddle-supporting riser 10, adjustable crank and

sprocket - carrying bracket 12, and brake mechanism 13. The said frame is formed of two metallic tubes arranged side by side and preferably slightly separated at their forward portions, forming the backbone, curved to correspond to the contour of the front wheel at the intermediate horizontal portion rigidly joined by a lock-forging or other suitable connecting means, as shown at f, and the said tubes toward their rear end slightly diverge with relation to each other to form the fork for the rear wheel, each diverging leg of the fork preferably tapering rearwardly, all substantially as shown in Figs. 1 and 2. The 55 said lock-forging or connecting-web between the intermediate portions of the frame is to be properly apertured and otherwise formed and adapted to sustain and permit of the proper operation and effect of the parts hereinbefore mentioned as may be found necessary in construction, and more than one intermediate joining-web may be provided, if deemed necessary.

The rear tapering legs of the rear-wheel fork may retain a circular cross-section, or may, if preferred, be of elliptical cross-section, and again, if desired, the forks may be, in cross-section, of any desired form, as flat or are-shaped.

At the upper and forward end of the backbone is rigidly connected a head-frame, E, of suitable form to support and form bearings for the handle-bar or steering-spindle G, and the spindle J, carrying the front-wheel fork.

As in the present class of bicycles the wheels are geared or sprocketed down, whereby on one revolution of the crank two or more rotations may be imparted to the wheels, the slightest deflection of the front fork to either side will cause the forward wheel to depart widely from a straight course, and it requires the exercise of painful care and manipulation of the handle-bar to properly guide the machine.

The present improvement, to overcome the disadvantages mentioned, consists in providing a connection between the handle-bar spindle and front-fork spindle, whereby on the turning of the former a decreased motion will be imparted to the latter, and a large variety of expedients to this end may be employed.

The one shown in Figs. 2 and 4 consists of providing a spur-gear, m , of comparatively large diameter, on the fork-spindle, and a spur-gear, n , of reduced diameter, on the handle-bar spindle, and in order to secure a rotation of both spindles in the same relative directions a pinion, p , is interposed between the large and small gears.

As shown in Fig. 1, the head is formed in two tiers, q , one above the other, rigidly joined, and thus longer bearings for the spindles are insured, and it is desirable to duplicate the motion-reducing mechanism between the spindles to insure a more even working of the parts. Each tier of the bearing-head has a shallow rabbet-chamber, t , formed therein, within which the gearing or other equivalent mechanism may be disposed, said parts being covered by inclosing-caps s . In Figs. 5 and 6 motion-reducing devices for the purpose described are shown, the former consisting of a comparatively short lever, u , secured on the handle-bar spindle and acting by its outer end against the swinging end of a comparatively long yoke-lever, v , which by its other end is secured on the fork-spindle, a friction-roller, w , being preferably provided on the swinging end of the short lever, and in Fig. 6 is shown a yoke, v , attached by one end to the fork-spindle, having its swinging end portion formed with a segmental rack, x , and with which meshes a pinion, y , fixed on the handle-bar spindle, a considerable extent of rotation of which effects a lessened extent of rotation on the fork-spindle.

Other devices may be employed for the purpose described than those shown—such, for instance, as large and small sprocket-wheels or pulleys on the handle and fork spindles and a chain or belt between them.

What I claim as my invention is—

1. A frame for safety-bicycles, consisting of two tubes ranging in parallelism and joined together, curved at their forward end portion to form the backbone for the forward wheel,

and to the rear of which they extend horizontally and form suitable carrying-supports for other parts of the machine, as described, and the rear-wheel fork, substantially as and for the purpose described.

2. In a bicycle, the combination, with the forward and rear wheels, which are of substantially the same diameters, and a fork carrying the front wheel provided with a vertically-extending spindle-bearing for rotation in the stationary head of the bicycle, and a separate vertically-extending handle-bar spindle, also bearing for rotation in said head, of a motion-reducing connection on and between the said handle-bar and fork spindles, whereby on the rotation of the former a rotation of less extent is imparted to the latter spindle, substantially as and for the purpose described.

3. In a bicycle, the combination, with a suitable head-frame and the front fork having a spindle-bearing for rotation in said head, provided with a spur-gear, of the handle-spindle bearing for rotation in said head-frame provided with a spur-gear of less diameter than the one on the fork-spindle, and an intermediate pinion between and engaging said spindle-gears, substantially as and for the purpose described.

4. In a bicycle, the combination, with a suitable head-frame and the front fork having a spindle-bearing for rotation in said head, provided with a spur-gear, of the handle-spindle bearing for rotation in said head-frame, provided with a spur-gear of less diameter than the one on the fork-spindle, and an intermediate pinion between and engaging said spindle-gears, the said frame being provided with a rabbeted chamber, into which said gear-wheels are disposed, and a cap for inclosing the same, substantially as described.

GEO. T. WARWICK.
